UNITED STATES PATENT OFFICE.

JAMES L. SINCLAIR, OF POTLATCH, IDAHO.

SHADE-ROLL-OPERATING DEVICE.

1,053,658.

Specification of Letters Patent. Patented Feb. 18, 1913.

Application filed January 26, 1912. Serial No. 673,651.

To all whom it may concern:

Be it known that I, JAMES L. SINCLAIR, a citizen of the United States, residing at Potlatch, in the county of Latah and State of Idaho, have invented certain new and useful Improvements in Shade-Roll-Operating Devices, of which the following is a specification.

My invention relates to improvements in shade-roll operating devices, the primary object of the invention being to provide a generally improved "springless" shade-roll operating device, the invention being particularly adapted for use in connection with large shades and rolls, awning rolls, curtain rolls, and the like.

A further object of the invention is to place all the shade roll actuating or operating mechanism at one end thereof and entirely independent of the shade-roll, proper, and provide simple, cheap and efficient operating mechanism without the use of springs, the invention being particularly adapted for use in connection with heavy rolls and shades as above pointed out.

With the above mentioned and other ends in view, the invention consists in the novel construction, arrangement, and combination of parts, hereinafter described, illustrated in one of its embodiments in the accompanying drawings, and particularly pointed out in the appended claims.

Referring to the drawings forming a part of this specification, Figure 1, is a front elevation of a mounted shade-roll equipped with my improved operating device. Fig. 2, a side elevation of the same. Fig. 3, an enlarged front view of the bearing bracket housing detached. Fig. 4, a similar view of the same with the cap or cover of the two-part bearing bracket removed, showing the arrangement of the internal operating mechanism. Fig. 5, an end view of the same. Fig. 6, a cross sectional view taken on line 6-6 of Fig. 4. Fig. 7, a perspective view of the improved shade-roll pintle shaft detached.

Similar numerals of reference designate like parts throughout all the figures of the drawings.

The improved shade-roll operating device comprises a pintle shaft 1, provided with a winged head 1^a, adapted to be mounted in the end of an ordinary wooden shade-roll. 55 The opposite end of the shade roll may be mounted in any suitable and convenient

manner and the shade 3, may be mounted upon and secured to the roll 2, in the usual manner, and is preferably weighted at its lower end by means of a rod or bar 4.

As a convenient means for mounting the bearing or pintle shaft 1, a two-part bearing bracket or housing is provided, said bearing bracket or housing comprising a base or bracket member 5, having wings 5^a, provided with screw openings for securing the same to a window frame, as indicated in Figs. 1 and 2 of the drawings. The base member 5, is provided at its ends with bearing members 5^b, for the reception of the pintle shaft 1, and as a means for removably mounting said shaft 1, in the bearing bracket housing as well as covering the operating mechanism hereinafter described, a cap or cover member 6, is provided, said cap or cover member being provided with companion bearing members 6^a, and as a means for securing the cap or cover in position, the same is provided with lugs 6^b, provided with openings adapted to register with similarly shaped or companion lugs 5^c, on the base member and secured by means of securing bolts and nuts 7.

As a means for operating the shaft 1, and roll 2, in a direction adapted to elevate or roll up the shade 3, an operating strap 8, is provided, said strap being adapted to be wound upon the shaft 1, in an opposite direction to that of the shade 3, on the roll 2, so that when the strap 8, is pulled down through the medium of the handle 8^a, the shade 3, will be wound up upon the roll 2, and when the shade 3, is pulled down the strap 8, will be wound up upon the shaft and inside of the two-part bearing bracket 9^a housing or casing, the cap or cover member 6, being provided with a slot opening 9, at its lower side for the passage of the strap 8. The lower end of the strap 8, is preferably provided with a weight 10, to counter 100 or over balance the weight of the shade 3, and rod or bar 4, in the various positions to which the shade may be adjusted, and as a means for holding the roll in any position to which it may be adjusted and preventing 105 its paying out of the weighted strap 8, a ratchet wheel 11, is mounted on the shaft 1, and, in the present instance, as an integral part of the actuating spool or drum herein-after described, the teeth of said ratchet 110 wheel extending in a direction opposite to the direction of rotation of shaft 1, and roll

2, in the paying out or lowering of the shade 3, said ratchet teeth being adapted to be normally engaged by means of a pivoted pawl member 12, mounted, in the present 5 instance, within one end of the base bracket member 5, and provided with a counter-weight member 12^a, adapted to normally hold the free end of the pawl member into engagement with the ratchet teeth and 10 against the action of the pendant pawl release cord 13, extending downwardly along the side of the operating strap 8.

As a convenient means for mounting and attaching the operating strap 8, to the pintle shaft 1, within the two-part bearing bracket housing, said pintle shaft, in the present instance, is provided with an actuating spool or drum 14, detachably mounted upon the pintle shaft 1, by means of a 15 cross pin 15 (see Fig. 4) said pin extending through suitable openings in the spool or drum 14, and through an opening 1^b (see Fig. 7) in the pintle shaft 1.

When it is desired to roll up or elevate 20 the shade 3, the pawl 12, is released from engagement of the ratchet wheel 11 through the medium of the pawl release cord 13, with one hand and if the weight 10 in the strap 8 is not sufficient to elevate the shade to the 25 position desired, the operating strap 8, may be pulled down with the other hand. When it is desired to pull the shade down, the latter may be pulled down in the usual manner thus causing the operating strap 8, to 30 be wound on the spool or drum 14, the pawl member 12, riding upon the ratchet teeth of the wheel 11 until the desired position is 35 reached.

From the foregoing description, taken in 40 connection with the accompanying drawings, the operation and advantages of my invention will be readily understood.

Having thus described an embodiment of 45 my invention, what I claim and desire to secure by Letters Patent is,—

1. A shade-roll operating device, comprising a pintle shaft provided with a winged head, a spool removably mounted thereon

and provided with ratchet teeth extending in a direction opposite the shade unrolling 50 rotation of said shaft, a two-part bearing bracket housing surrounding said spool and provided with a slot, a weighted pawl in said housing normally engaging said ratchet teeth, a strap on said spool extending 55 through said slot, and a pendant cord connected to said pawl and adapted to release the latter from said ratchet teeth.

2. A shade-roller operating device, comprising a shade-roll provided with a bearing 60 shaft at one end, a bearing bracket for said shaft, a ratchet wheel carried by said shaft, a weighted shade mounted on said shade-roll, a counterbalanced pawl normally engaging said ratchet wheel and adapted to 65 prevent the unrolling of said shade-roll, an operating strap wound upon said shaft in an opposite direction to that of said shade, and a pawl releasing cord depending from said pawl and adapted to release the latter 70 from said ratchet wheel when said operating strap is pulled down to actuate said shade-roll and roll said shade on the latter.

3. A shade-roll operating device, comprising a bearing bracket housing consisting of 75 a base member and a removable bearing cap or cover, a shade-roll pintle shaft mounted in said bearing bracket housing, a winding spool carried by said pintle shaft within said housing, a ratchet wheel on said pintle 80 shaft, a counterbalanced pawl within said housing normally engaging with said ratchet wheel, an operating strap wound on said spool in the direction opposite the direction of the teeth of said ratchet wheel, and a pawl release cord carried by said pawl and adapted to release the latter when said operating strap is pulled to actuate said spool and pintle shaft in a shade rolling 85 direction.

In testimony whereof I have affixed my signature in presence of two witnesses.

JAMES L. SINCLAIR.
